UNITED STATES PATENT OFFICE.

MILLET S. STEWART, OF LOWER NEGUAC, NEW BRUNSWICK, CANADA.

REMOVABLE AX-BIT.

1,292,531.

Specification of Letters Patent. Patented Jan. 28, 1919.

Application filed July 30, 1917. Serial No. 183,389.

To all whom it may concern:

Be it known that I, MILLET S. STEWART, a subject of the king of Great Britain, residing at Lower Neguac, New Brunswick, Canada, have invented new and useful Improvements in Removable Ax-Bits, of which the following is a specification.

The invention to be hereinafter described relates to removable ax bits.

10 In order to more clearly disclose the construction, operation, and use of the invention, reference should be had to the accompanying drawings forming part of the present application. Throughout the several 15 figures of the drawings like reference characters designate the same parts in the several views.

In the drawings:—

Figure 1 is a side elevation;

20 Fig. 2 is a front view;

Fig. 3 is a rear view;

Fig. 4 is a bottom plan view of an ax head;

Fig. 5 is a top plan view of the bit;

25 Fig. 6 is a central, longitudinal, vertical cross section through the head, showing the bit in position;

Fig. 7 is a side elevation of the head; and,

Fig. 8 is a side elevation of the bit.

30 The main objects of the invention are to provide a simple, efficient, durable, compact, and economical removable ax bit which may be quickly and readily removed and replaced, together with means for limiting the 35 movement of said bit, relatively to said head, and for preventing the bit from becoming accidentally disengaged from the head.

Referring to the drawings in detail, 1 indicates the head having an arcuate lower 40 end 2 terminating, at the front, in a short straight portion. This end is provided with a channel 3 of egg-shape or oval lateral cross section, as more clearly shown in Fig. 3. On reference to Figs. 2-5 it will be noticed that the walls of channel 3 taper from front to rear. This is due to the fact that the arc runs downwardly from front to rear, cutting through progressively thinner portions, and, since the channel is of the same cross section throughout, the walls must become thinner, at the rear end. The channel thus formed, leaves two horizontal shoulders 4 at the forward end of each wall 5 of 55 the channel 3, for a purpose to be later disclosed. The cutting edge of the ax is formed

on a removable bit 6, the upper end of which is provided with a tongue, feather, or tenon 7 of a cross section and curvature complementary to that of the channel 3 and having 60 curved walls 8 complementary to the ends of the walls of the channel 3 and terminating in shoulders 9 coöperating with the shoulders 4. The oval shape of the tongue and channel prevent the bit and head from 65 dropping apart. In cutting, the force of the blow tends to drive the bit forward and upward in the direction of the curvature of the walls 5, but the engagement of shoulders 9 on shoulders 4 prevents this. Consequently, the bit is kept, normally, in exactly 70 the right position. Also, by having the engaging walls 8 and 5 and the channel and tongue on the curvature shown, the force of the blow, as between the removable bit and 75 the head, is distributed. Furthermore, by having the wider or thicker part of the walls 5 and 8 at the front of the head, they are in the proper position to receive the greater 80 part of the force of the stroke.

In assembling the ax head, it is only necessary to slide the tongue 7 into channel 3 and the ax is instantly ready for use.

It is thought that the construction, operation, and use of the invention will be clear 85 from the preceding detailed description. Changes may be made in the construction, arrangement, and disposition of the several parts of the invention, without in any way departing from the field and scope of the 90 invention, and it is meant to include all such within this application wherein only a preferred form has been disclosed, by way of illustration.

Having thus described my invention, what 95 I claim and desire to protect by Letters Patent is:—

1. In combination, an ax head having a longitudinally extending, downwardly curved channel running throughout its lower 100 face from front to rear and provided with stop shoulders at the sides of the forward end of the channel, said shoulders being formed by departure from the curve of the bottom of the channel, and a removable bit 105 provided with a coöperating tongue and having coöperating stop shoulders.

2. In combination, a tapered ax head having a downwardly curved channel of uniform oval lateral cross section and running 110 through the head from front to rear and provided with correspondingly curved wall

edges increasing in width from rear to front and terminating in stop shoulders formed by departure from the curve of the bottom of the channel; and a removable bit having 5 a coöperating tongue extending from front to rear and provided with coöperating correspondingly curved wall edges increasing

in width from rear to front and terminating in coöperating stop shoulders.

Signed at Newcastle, New Brunswick, 10 Canada, this twenty fourth day of July, 1917.

MILLET S. STEWART.

Copies of this patent may be obtained for five cents each, by addressing the "Commissioner of Patents, Washington, D. C."
